UNITED STATES PATENT OFFICE.

WILLIAM W. WALLACE, OF BUCYRUS, OHIO.

BRICK-HANDLING FORK.

Application filed January 27, 1921. Serial No. 440,324.

To all whom it may concern:

Be it known that I, WILLIAM W. WALLACE, a citizen of the United States, and a resident of Bucyrus, in the county of Crawford and State of Ohio, have invented an Improvement in Brick-Handling Forks, of which the following description, in connection with the accompanying drawings, is a specification, like letters on the drawings 10 representing like parts.

In my present invention I have devised a brick lifting apparatus which I have designated as a brick handling fork, the same being intended primarily for use in unloading brick from a stack, pile or the like, such as a kiln. In the art of handling brick by means of mechanical apparatus such as mechanical setting machines, such for example as those shown in the U. S. patent to R. C. 20 Penfield, No. 1,205,562, issued November 21, 1916, mechanical setting machines have been developed and successfully used in the building of brick kilns wherein a unit of stacked brick in desired spaced relation was 25 delivered to and unloaded from a setting apparatus directly into the kiln. However, it has been impractical heretofore to utilize mechanical brick lifting devices to remove from a kiln after the bricks are burned, a 30 unit or a considerable quantity of brick. This difficulty has been caused by the fact that the rows or courses of brick in a kiln shrink unevenly and vary in their horizontal alinement. Not only does each course 35 of brick shrink in a somewhat different manner from those adjacent it, when burned, but such variation is apt to be distorted throughout a plurality of courses. Consequently the rows of brick in a kiln, after the kiln is 40 burned, are in a very wavelike formation, the rows or courses appearing in undulating lines of varying extent, but mostly distorted from a horizontal plane. Because of this fact it has been impractical to use a setter 45 with brick engaging fingers in alinement as the line of the brick itself was so distorted and never in alinement after the brick are burned.

In my present invention I have aimed to 50 provide a mechanical brick handling apparatus capable of use to be applied to the face of a kiln of burned brick irrespective of the disalinement of the rows or courses of brick, and to enable the fingers of the apparatus to follow the undulations or dis- 55 tortions in the rows of brick so that the fin-

gers can be fitted at any desired point and substantially a full unit of brick can thus be unloaded from a kiln, as was set when building the kiln. To this end I provide a 60 setting apparatus having each brick lifting and engaging finger independently adjustable with regard to the vertical position of said finger on the apparatus. Furthermore I provide each finger with a tapered point so 65 that as the apparatus is applied to the brick and forced inwardly, each finger will, independently of each other, follow the line of the course of brick to which it is applied. It will be appreciated that burned brick in 70 the kiln are in spaced or "hacked" relation and therefore the narrow forward end of each finger will enable the apparatus to be forced into the interstices between the brick, following the lines of least resistance, and 75 permitting the finger to assume a higher or lower vertical position to enable it to be thus forced into the mass of brick in the kiln.

When the apparatus is in place, preferably under a considerable plurality of rows 80 of brick, in order to remove the unit, it is then lifted, and all the brick engaging fingers which were disaligned during the process of applying the unloading fork to the brick stack, will settle down into the same 85 horizontal plane, against suitable stops, and thus the entire mass of brick lifted out as a unit and simultaneously straightened, realigned and settled into a horizontal plane 90 at the bottom portion.

Therefore the unit can be set down from the unloading fork with the bottom courses even and adapted to rest firmly and squarely upon the car, platform, or other support.

Referring to the accompanying drawings, 95 wherein the preferred embodiment of the invention is illustrated,

Fig. 1 is a front view of an unloading fork;

Fig. 2 is a side view at one end.

The unloading fork or apparatus comprises a framework adapted to be swung from an overhead support, either a turn-table or a four point suspension, to a crane, traveling carriage, beam or the like. A 105 light, strong, rigid framework is therefore provided, consisting in a pair of arms 1 and 2 from which the eye-bolts or links 3, 3 and 4, extend, affording the four-point suspension. To these arms 1 are attached a pair 110 of vertical extending plates 5, 5, and 6, 6, the latter extending rearwardly and spaced

slightly from the front plates 5, as shown in Fig. 2, and united at the base portion by brackets 16, 16, to which is secured a horizontal plate 10 extending substantially throughout the entire length of the apparatus. Cross-braces 11, 12, 13 and 14 extend from the frame plates 5 to the plate 10, being securely bolted as illustrated in Fig. 1.

This plate 10 has a plurality of perforations therethrough, each one being suitable to receive, freely, a rod 20, threaded at its uppermost portion and carrying a cup bearing 21 to contact with a coiled spring 22, the latter being tensioned between the plate 10 and the cup bearing 21, said cup being held in adjusted position by lock nuts 24 and 25. In the apparatus shown in the attached drawings I have provided 13 brick engaging fingers and therefore in the plate 10 are 13 perforations and a similar number of springs 22, rods 20, and attached members. Any desired number or plurality can be supplied and with the fingers spaced as desired.

These fingers 30 extend forward a sufficient distance to pick up and transport the desired unit of brick to be handled, the spacing of the supporting eye bolts 3 and 4 being arranged to afford a horizontal position of the apparatus whether loaded or unloaded.

Each finger 30 is mounted to move independently in a vertical relation with the adjacent fingers, as above explained, to be fitted within the interstices within the brick when being applied to the kiln or stack for picking off a mass of brick to be removed.

These fingers 30 are preferably formed to be carried by a vertical sliding carriage 33, the fingers being formed with a vertical rod 34 and a flanged top portion 135 to afford a dovetailed engagement with a corresponding socket portion 136 of the carrier 33. I have here shown the carrier 33 as adapted to encircle and partially enclose a bearing member 35, the latter being formed with a

flange 36 adapted to be secured underneath the plate 10 and, in alinement with the springs 21 and rod 20 by a plurality of bolts 37 and 38. This member 35 is formed hollow as indicated at 39, to receive the rod 20 which extends therethrough and is attached to the carriage 33 by pins 40 and 41. The member 35, formed hollow to receive said rod 20, is also provided with slots 44, extending laterally through below a predetermined point to permit the pins 40 and 41 to slide downwardly when desired, the uppermost pin 40 contacting with the top of the slot 44 when the carrier 33 and consequently the fingers 30 are raised in uppermost position, as shown in Fig. 2. The member 35 is formed with forward and backward tracks upon surfaces upon which

rollers 45 at the front and 46 and 47 at the rear of the carrier 33 are adapted to travel, these preferably being in sufficiently tight

frictional engagement to normally hold the carrier 33 and its attached fingers 30 in any vertical position to which the member may be pushed, the spring 22 serving to counteract the weight thereof to accomplish this function. A stop against too great downward movement is provided by forming the bottom portion of the member 35 as shown at 49 and also by the fact that the cup 21 carried by the rod 20 will compress the spring 22 to its limit and then hold the carriage 33 and attached member 30 against forward or downward movement while the top of the slot 44 acts as a limit in upward movement. Between the range of these two stops each carriage 33 and attached finger 30 are independently vertically movable, to permit the finger 30 to find its way through the course of brick to which it is being applied when using the apparatus as an unloading fork.

When the apparatus is applied to the face of a brick kiln, stack or the like, all the fingers 30 may be in different horizontal position and with no torsional strain on the apparatus nor on each other. As soon as lifting strain is applied, then all the fingers 30 settle down to the limit of the vertical movement afforded, and thus the lower part of the unit of brick being picked out of the kiln by the fork, is straightened up and realined into a horizontal plane, thereby greatly facilitating unloading of the unit, insuring its being maintained in horizontal position while transported, and truing up the entire unit or stack thus handled.

It will be appreciated that my brick handling apparatus can be utilized as an ordinary bricksetter by having all the fingers 30 and their supporting travelling carriages 33 in downward position and thus being maintained horizontal. When so positioned the brick handling fork can be employed like an ordinary bricksetter, such as that of said Penfield patent and advantageously utilized in setting brick in the kiln, taking them off the drier car or other conveyance.

I believe that the provision of a brick handling apparatus or fork capable of having its brick engaging fingers disaligned for loading purposes—as well as the provision of a brick handling apparatus equally suitable both for taking green brick in stacked units from a drier car or the like and building them into a kiln for burning and then thereafter removing the burned brick from a kiln irrespective of the disalinement of the rows of brick by the burning, are distinct novelties and I wish to claim these features herein broadly.

My invention is further described and defined in the form of claims as follows:

Brick handling apparatus of the kind described, comprising an overhead support, a plurality of horizontally extending brick

engaging fingers and means connecting said fingers and said support consisting in a vertical bearing rigidly attached to said frame, a carriage adapted for vertical sliding movement on the bearing member and carrying the horizontal fingers, anti-friction members between said carriage and said

bearing and positive stop means cooperating with said anti-friction members to limit the vertical movement of said carriage. 10

In testimony whereof, I have signed my name to this specification.

WILLIAM W. WALLACE.
